(57) **CLAIM**

We claim the ornamental design for a tabletop remote load control device, as shown and described.

DESCRIPTION

FIG. 1 is a perspective view of a tabletop remote load control device according to a first embodiment of our new design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view of a tabletop remote load control device according to a second embodiment of our new design.

FIG. 8 is a front view thereof; and,

FIG. 9 is a bottom view thereof, the left side, right side, and top views, respectively, of the second embodiment being identical to the left side, right side, and top views of the first embodiment.

The rear views form no part of the design and are omitted.
